UNITED STATES PATENT OFFICE

JOSEPH LEISCH, OF TRYON, NORTH CAROLINA, ASSIGNOR TO THE JOHN CHURCH COMPANY, OF CINCINNATI, OHIO, A CORPORATION OF OHIO.

PLAYER-PIANO.

1,066,633.

Specification of Letters Patent.

Patented July 8, 1913.

Application filed March 18, 1912. Serial No. 684,444.

To all whom it may concern:

Be it known that I, JOSEPH LEISCH, a citizen of the United States, and a resident of Tryon, in the county of Polk and State of North Carolina, have invented certain new and useful Improvements in Player-Pianos, of which the following is a full, clear, and exact description, reference being had to the accompanying drawings, 10 forming part of this specification.

My invention relates to player pianos in which the piano keys are connected with a series of power pneumatics, which are operated mechanically by pneumatic power, 15 released by the exposure of openings in a tracker board by the movement of the specially prepared slotted or perforated sheets of music, which are propelled over the tracker board to actuate the pneumatic devices. 20

The object of my invention is to provide a construction for such player pianos whereby selected notes may be accented, or a solo part carried in the playing of the instrument simultaneously with the playing of other notes in the score. 25

The invention consists of that certain novel construction and arrangement of parts to be hereinafter particularly pointed 30 out and claimed, whereby the character of the stroke on the keys may be effectually controlled through the tracker board by pneumatic action on the checks or stops for the actuating members of the power pneumatics, in order to vary the strength of the 35 stroke of the pneumatic and thus the tonal effects of the instrument as desired.

In the drawings, Figure 1 is a vertical section of the pneumatic chest of the player 40 piano, taken through one of the pneumatics. Fig. 2 is a rear elevation of a portion of the pneumatic chest.

While I have not thought it necessary to illustrate the complete player piano construction, it will be understood that the ordinary pneumatic player chest is provided with vacuum chambers and suitable means for creating the vacuum, and the usual tracker board and tracker tubes forming 45 the necessary passages over which the perforated music sheet passes for releasing the vacuum to operate the selected pneumatics which are coupled with the piano action. Primary and secondary pouches and valves 50 and power pneumatics are provided for each

note, and the player chest is divided into two parts as usual, one half of the chest for the bass and the other half for the treble notes on the piano. In order to economize space, the several power pneumatics, one for each note, are arranged in pairs of three in staggered relation to each other. 60

The body of the pneumatic chest is represented by 1, and in the upper portion of the chest a primary vacuum chamber 2 is located, a common chamber for all of the tracker tubes for each half of the player piano. The several tracker tubes 3 are connected with this common vacuum chamber 70 by the passageways 4 connecting with the primary pouches 5. The pouches 5 operate the valves 6, provided with the valve disks 7 and 8 to close or open the respective individual passageways 9 to the vacuum chamber 2 or the outer air. In their normal position, the pouches 5 are deflated, and the passageways 9 are open into the vacuum chamber 2 and closed to the outer air. These passageways 9 extend to their respective ports 10 in the secondary vacuum chamber 11 in which are located the secondary pouches 12 which operate the valves 13, opening or closing the ports 14 into the secondary vacuum chamber 11 or the ports 85 15 to the outer air into the passageways 16, which each leads to and opens into its respective power pneumatic 17. The respective power pneumatics 17 are of the usual bellows type, comprising the movable member 18 and the fixed member 19 with bellows fold 20, while the movable member 18 is provided with an extension 21, arranged to contact with a lug 22 on the sticker 23 of its respective piano action. 95

Mounted inside the pneumatic is a strip of spring metal 24, suitably secured to the under surface of the fixed member of the pneumatic at 25. The free end of this spring plate 24 is preferably provided with a felt washer 26, which bears against the central portion 27 of a pouch 28, which pouch, of leather or other suitable material, is secured across and closes the lower end of a cap 29 which is screwthreaded or otherwise secured in a screwthreaded recess in the fixed member of the pneumatic. This cap 29 is provided with a screwthreaded set screw 30 which is centrally mounted in the cap, with its inner end projecting inside 105 110

the cap toward the pouch 28, forming a fixed adjustable stop for the central portion of the pouch 27 and the end 26 of the spring plate 24.

5 The cap 29 is provided with a tube 31 opening therein, which connects with the passageway 32 leading to an individual chamber 33 in the pneumatic chest for the passageway. These chambers 33 are provided with ports 34 to the outer air and ports 35 into a common vacuum chamber 36 in the pneumatic chest for all the passageways. Located in the chamber 36 are a series of pouches 37 for the passageways 38, each provided with a secondary tracker tube 39 running to supplemental tracker openings in the tracker board. The pouches 37 are each provided with the double-seated valve 40 opening and closing the chambers 33 to the outer air and to the vacuum chamber 36.

It will be understood that each power pneumatic is provided with a similar construction and arrangement of valves and passageways to that just described.

25 For a contact member for each of the movable members 18 of the power pneumatics, I provide the cushion 41, of felt or other suitable material, located underneath and in line 30 with the spring plate 24. This cushion is arranged for longitudinal adjustment in any desired way, and as illustrated is mounted on the screw 42, which projects through a narrow longitudinal slot 43 in the movable member, with the slot protected and covered 35 for all adjustments by the cover plate 44. The screw 42 is provided with the winged nut 45 for holding the contact cushion 41 in any desired position of adjustment within 40 the limits of the length of the slot, the cushion being so arranged for all adjustments that it will contact with the spring 24 in the upward movement of the movable member between the free end 26 and the 45 fixed inner end of the spring.

The movable members of the power pneumatic of the selected power pneumatics will be operated in the ordinary way through the tracker board release and tracker tubes 3 50 and their connections, and in the upward movement the movable member will be checked by contact with the spring plate 24, with the outer end bearing against the pouch 28, which provides an air cushion as a stop, 55 and for ordinary effects this air cushion will furnish a sufficient check and stop for the pneumatic action.

In the event that it is desired to accent 60 any of the notes, or to carry a solo part, the music sheet will be provided with supplemental slots to open the desired supplemental tracker tubes 39. The effect of this will be to close the outer air passageway 65 from the selected pneumatic through the tube 31, passageway 32 and port 34, and

open said passageway 32 to the vacuum chamber 36, thus subjecting the pouch 28 to the suction of the chest and permit the free end of the spring plate to come in contact with the set screw 30 without the intervention of any air cushion. The set screws 30 and the position of the striking cushions 41 are properly adjusted, so that for the normal unaccented operation of the several pneumatics, the air cushion produced by the pouch 28 in closing the cap 29 shall be a necessary part of the stop. When this air cushion is withdrawn by subjecting the interior of the cap to the exhaust, the action of such pneumatics will necessarily be sharper and more pronounced, and thus the tones desired will be properly accented.

Having thus described my invention, what I claim as new and desire to secure by Letters Patent, is:

1. In a player piano, a power pneumatic having a fixed and a movable member, a stop for the power pneumatic to serve as an abutment for the movable member comprising a relatively fixed stop and an air cushion stop interposed between the fixed stop and the movable member of the pneumatic, with means for decreasing the pressure within the air cushion stop to bring the fixed stop into action.

2. In a player piano, a power pneumatic having a fixed and a movable member, a stop for the power pneumatic to serve as an abutment for the movable member comprising a relatively fixed stop and an air cushion stop interposed between the fixed stop and the movable member of the pneumatic, with a primary pneumatic pouch and tracker tube to control the pressure in the air cushion stop, to bring the fixed stop into action.

3. In a player piano, a power pneumatic having a fixed and a movable member, a stop for the power pneumatic, comprising a relatively fixed stop and a pneumatic pouch within which the fixed stop projects, a strip of resilient metal secured at one end within the power pneumatic, to the fixed member thereof, with the free end thereof engaging the pneumatic pouch, and a contact projection on the movable member of the pneumatic to contact with said spring with means for decreasing the pressure within the pouch to bring the fixed stop into action.

4. In a player piano, a power pneumatic having a fixed and a movable member, a stop for the power pneumatic, comprising a relatively fixed stop and a pneumatic pouch within which the fixed stop projects, a strip of resilient metal secured at one end within the power pneumatic to the fixed member thereof, with the free end thereof engaging the pneumatic pouch, and a contact projection on the movable member of the pneumatic to contact with said spring, with a primary pneumatic pouch and sup-

plementary tracker tube to control the pressure in the pneumatic stop to bring the fixed stop into action.

5. In a player piano, a power pneumatic having a fixed and a movable member, a stop for the power pneumatic, comprising a relatively fixed stop and a pneumatic pouch within which the fixed stop projects, a strip of resilient metal secured at one end within the power pneumatic to the fixed member thereof, with the free end thereof engaging the pneumatic pouch, and a longitudinally adjustable contact projection on the removable member of the pneumatic to contact with said spring intermediate the point of engagement with the pouch and the fixed end thereof, with means for decreasing the pressure within the pouch to bring the fixed stop into action.

10 6. In a player piano, a power pneumatic

having a fixed and a movable member, and a stop to serve as an abutment for the said movable member consisting in an air cushion interposed between the movable member and the fixed member, with means for decreasing the pressure within the air cushion to remove it from its interposition.

15 7. In a player piano, a power pneumatic having a fixed and a movable member, and a stop to serve as an abutment for the movable member interposed between the movable member and the fixed member consisting in an air cushion, with means including a primary pneumatic pouch and a tracker tube to control the pressure within the air cushion to remove it from its interposition.
